US00D613289S

(12) **United States Design Patent**
Alegiani et al.

(10) **Patent No.:** US D613,289 S
(45) **Date of Patent:** ** Apr. 6, 2010

(54) **CODE READER**

(75) Inventors: **Monica Alegiani**, Silvi (IT); **Luigi Frison**, Mirano (IT)

(73) Assignee: **Datalogic Mobile S.r.l.**, Lippo di Calderara di Reno (Bologna) (IT)

(**) Term: **14 Years**

(21) Appl. No.: **29/323,942**

(22) Filed: **Sep. 3, 2008**

(30) **Foreign Application Priority Data**

Mar. 5, 2008 (EM) 000891544-001

(51) **LOC (9) Cl.** **14-02**

(52) **U.S. Cl.** **D14/426; D14/429**

(58) **Field of Classification Search** ..... D14/420, D14/426-430, 453, 346, 341, 347, 412, 138; D13/107, 184; 358/473; 235/462.43, 462.45, 235/462.47, 462.48, 462.44, 462.46, 487, 235/472.01, 472.02, 145 A, 145 R; D10/78; 324/426; D3/273; 710/73; D18/7; 361/679; 382/313, 321; 455/575.1, 561, 572; 345/156, 345/168, 169, 172, 173, 87

(57) **CLAIM**

We claim the ornamental design for a code reader, as shown and described.

DESCRIPTION

FIG. 1 is perspective view of a code reader according to the present invention;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.
